UNITED STATES PATENT OFFICE

2,220,179

RAIL JOINT

Albert G. C. Schroeter, South Chicago, Ill.

Application August 7, 1939, Serial No. 288,751

1 Claim. (Cl. 238—191)

The invention relates to rail joints.

One object of the invention is to provide a rail joint which is efficient in use and which is adapted to prevent cracking of the rail web.

Another object of the invention is to provide an improved rail joint which comprises splice-bars and a bridge-plate having its lower side provided with reinforcement substantially coplanar or flush with the bottom faces of the members 10 of the splice-bars which underlie the base flanges of the rail so that both the bridge-plate and the splice-bars may be uniformly supported upon the ties.

Another object of the invention is to provide a rail joint which comprises splice-bars and a bridge-plate beneath the base flanges, the splice-bars being reinforced to adequately support the ends of the rails when the splice is between the ties.

Other objects of the invention will appear from the detailed description.

The invention consists in the several novel features hereinafter set forth and more particularly described in the claim at the conclusion hereof.

In the drawing: Fig. 1 is a side elevation of a rail joint embodying the invention. Fig. 2 is a section taken on the line 2—2 of Fig. 1. Fig. 3 is a section taken on the line 3—3 of Fig. 1. Fig. 4 is a perspective of the bridge-plate. Fig. 5 is a perspective of one of the splice-bars. Fig. 6 is a side elevation illustrating a modified form of the invention in which the joint is applied to rails between the ties. Fig. 7 is a section taken on line 7—7 of Fig. 6. Fig. 8 is a perspective of one of the splice-bars shown in Figs. 6 and 7.

The invention is exemplified as applied to rails *a* of the standard type and comprising a head *a*¹, a web *a*², and base flanges *a*³. The contiguous ends may be biased or transverse.

The rail joint comprises a pair of splice-bars *b* and *b*¹ and a bridge-plate *c* secured under the base flanges of the rails by the splice-bars. Each splice-bar comprises a vertical member *10*, the inner face of which fits against, and has clamping engagement with, the side faces of the web *a*² of the rail sections; a laterally and downwardly inclined integral member *11* extending over and having loading and wedging engagement with the upper inclined face of the flanges *a*³ at one side of the rails; a vertically and downwardly extending member *12* at the outer side of, and with clearance around, the outer edge of the base flanges *a*³ and the bridge-plate; and an integral inturned and laterally extending member *13* disposed under the outer portion of the base flange.

The members *10* terminate below the heads of the rail so the loading on the rails will be transmitted through the web to the joint. The bridge-plate *c* has a flat top-face *14* which fits against the bottom-face of the rail flanges; edges *15* which are flush with the edges of the base flanges and a central reinforced or thickened portion *16*, the bottom-face *17* of which is flush or substantially coplanar with the bottom faces of the inturned members *13* of the splice-bars. Between its reinforcement *17* and edges *15* the splice-bars are inclined upwardly and outwardly, as at *18*, and the abutting faces of members *13* are correspondingly inclined for wedging engagement. The sides of reinforcement *17* are spaced slightly from the inner ends of members *13* of the splice-bars to leave clearance for the clamping of the splice-bars to the rails. The wedging engagement of members *11*, *13* of the splice-bars and the bridge-plate clamp the bridge-plate against the bottom of the rails. Bolts *19* extend through holes in the members *10* of the splice-plate and the webs *a*² of the rails and are adapted to securely clamp the splice-bars sidewise into engagement with the rails. This clamping forces members *11* of the splice-bars into loading engagement with the base flanges, clamps the inner faces of members *10* securely against the sides of the web *a*² of the rails, and forces the bridge-plate into loading engagement with the bottom of the rails. The bottom faces of members *13* of the splice-bars and face *17* of the bridge-plate are flush or substantially coplanar so that when the joint rests upon a railway tie *d*, as shown in Figs. 1, 2 and 3, both the bridge-plate and splice-bars will engage the tie for efficiently supporting the joint. The upper edges of members *10* of the splice bar terminate below the head *a*¹ of the rails because, if the splice-bars extend to the rail-head, fracture of the web frequently results from the pounding of the wheels against the rail-head adjacent the joints. By transmitting the loading through the web and base to the bridge-plate, the reinforcing portion *16* of the bridge-plate extends from end to end thereof to uniformly reinforce the plate throughout its length.

Bolts *20* extend through the splice-bars below the base of the rail and beyond the ends of the bridge-plate to secure the bridge-plate against endwise movement relatively to the rail and splice-bars, and also to assist in retaining the members *13* of the splice-bars against spreading. Locating these bolts beyond the ends of the

bridge-plate, avoids the necessity of forming holes in the plate.

The thickness of the reinforcement **16** of the bridge-plate and the combined thickness of the **5** marginal portions of the bridge-plate and members **13** of the splice-bar, is substantially equal to the thickness of the usual tie-plate so that the joint will support the rails in alignment with the support furnished by the tie-plates on the **10** ties between the joint.

In the modification illustrated in Figs. 6 and 7, the invention is exemplified in a rail-joint adapted to support the ends of the rails when they meet between ties. In this form of the **15** invention the bridge-plate and the splice-bars are of the same construction hereinbefore described, except that the splice-bars are provided with downturned flanges **21**. Bolts **22** extend through flanges **21** and draw the splice-bars together below the bridge-plate and the rails. The splice-bars comprise members **10^a** for engaging the web, members **11^a** for providing loading and wedging engagement between the splice-bars and the base flanges, members **12^a** extending around the edges **20** of the base flanges of the rail and the side-margins of the bridge-plate, and members **13^a** having wedging engagement with the side-margins of the bridge-plate. The flanges **21**, depending from the inner ends of members **13^a**, adapt the **25** joint for supporting the rail-ends between, and independently of, adjacent ties. The bridge-plate in this construction is also held against endwise movement by bolts **20**.

In practice, the splice-bars and bridge-plate **30** can be formed of rolled stock. The construction is one which provides a joint of comparatively light weight, because it is possible to use lighter and shorter joints than those used in standard constructions. It is also possible to apply the rail joints to existing tracks with the use of tie-plates which correspond in thickness to the **35** bridge-plate. While four bolts have been shown

for clamping the splice-bars to the rails, in some instances two are sufficient, the length of the joint being varied according to the weight of the rails.

The invention is not to be understood as restricted to the details set forth, since these may be modified within the scope of the appended claim, without departing from the spirit and scope of the invention. **5**

Having thus described the invention, what I **10** claim as new and desire to secure by Letters Patent is:

In a rail joint, the combination of rails each comprising a head, a web, and base flanges, splice-bars spanning the rails and comprising **15** members having vertically extending inner faces for clamping against the sides of the rail webs, members having loading engagement with the top of the base flanges, members underlying the rails and members extending around the outer **20** edges of the base flanges, the members of each splice-bar being integral, a bridge-plate underlying and abutting against the bottom faces of the rails, the underlying members of the bars having their inner sides spaced apart and having **25** wedging engagement with the bottom faces of the margins of the bridge-plate, the bridge-plate having increased thickness between the inner sides of, and terminating inwardly of the ends of, the splice-bars below the rails, clamping **30** bolts extending through the splice-bars beneath the rails and outwardly of the ends of the bridge-plate for confining the bridge-plate against endwise movement, and bolts extending through the vertically extending members of **35** the splice-bars and the webs of the rails, the underlying members being provided with downwardly extending flanges outwardly of and at the sides of the portion of increased thickness on the bridge-plate, and bolts extending through **40** said flanges.

ALBERT G. C. SCHROETER.
